UNITED STATES PATENT OFFICE

139,161

DESIGN FOR A BRAKE SHOE TOOL

Rochelle E. Plumley, Everett, Wash.

Application September 2, 1943, Serial No. 111,051

Term of patent 14 years

(Cl. D54—13)

To all whom it may concern:

Be it known that I, Rochelle E. Plumley, a citizen of the United States, residing at Everett, in the county of Snohomish and State of Washington, have invented a new, original, and ornamental Design for a Brake Shoe Tool, of which the following is a specification, reference being had to the accompanying drawing, forming part thereof.

Figure 1 is a front elevational view of a brake shoe tool showing my new design, Figure 2 is a side elevational view thereof, and Figure 3 is a bottom plan view thereof.

I claim:

The ornamental design for a brake shoe tool, as shown.

ROCHELLE E. PLUMLEY.
